UNITED STATES PATENT OFFICE.

CARL H. SCHMIDT, OF PORT WASHINGTON, WISCONSIN.

ADJUSTABLE SPRUE.

1,361,188.

Specification of Letters Patent.

Patented Dec. 7, 1920.

Application filed March 15, 1920. Serial No. 365,826.

To all whom it may concern:

Be it known that I, CARL H. SCHMIDT, a citizen of the United States, and resident of Port Washington, in the county of Ozaukee and State of Wisconsin, have invented certain new and useful Improvements in Adjustable Sprues; and I do hereby declare that the following is a full, clear, and exact description thereof.

10 My invention relates to new and useful improvements in molders' tools, and has particular reference to sprues.

The primary object of this invention is to provide a sprue which can be adjusted as 15 to length so as to permit its use with patterns and flasks of various sizes.

An additional important object of the invention is to provide a sprue with means whereby it may be readily lifted from the 20 sand of the flask when the mold is complete so as to form the ingate therefor.

Still another object of the invention is to provide a two-part expandible sprue, parts of which are telescopically engageable and 25 are so held with respect to each other that disalignment is impossible.

With these general objects in view the invention resides in the novel features of construction, combination and arrangement of 30 parts which will be hereinafter more particularly described and claimed and shown in the accompanying drawing, wherein:

Figure 1 represents a substantially longitudinal sectional view on the plane of the 35 line 1—1 of Fig. 2 through an adjustable sprue constructed in accordance with the invention, the same being seated upon one end as it will be positioned when not in use.

Fig. 2 is a plan view of the seat end of 40 the device.

In the embodiment of the invention as depicted in the accompanying drawing, the same includes a main portion 1 and an extensible portion 2, the former being tapered 45 or relatively conical shaped and provided with a socket 3, the wall of which is cylindrical. This socket opens through the apex or small end of the main portion, the other end of which is provided with a cavity 4 surrounded by a flat seating surface 5.

Thus when the article is not in use it may rest upon this flat surface 5.

The extensible portion 2 of the sprue is cylindrical and substantially the same diameter as that of the socket 3. Also in 55 length it is substantially as long as the

socket is deep. The outer end of the extensible portion has an axially extending pin 6 for engagement in a socket of a pattern (not shown) as is customary in articles of this 60 nature.

The main portion 1 of the sprue is designed to telescopically receive the extensible portion 2 within its socket 3 and has a means for holding said extensible portion in 65 various adjusted and extended positions, the socket being provided with an axially extended threaded stem 7 which extends from the bottom thereof and terminates at a point slightly beyond the small end of the main 70 portion 1. The threads on this stem co-operatively engage the threads on the wall of a bore 8 formed in the inner end 9 of the extensible portion 2. This last mentioned portion is hollow as shown at 10 and therefore 75 receives the free end of the stem 7 as it is threaded through the bore 8. In view of the co-operative engagement between the walls of the socket 3 and the extensible member 2 together with that between the stem 7 and 80 the wall of the bore 8, said extensible portion is readily moved inwardly or outwardly of the main portion 1 and held in axial alignment therewith regardless of its position with respect thereto. A very read- 85 ily adjustable, yet exceedingly strong sprue, is thus provided.

The sprue is also equipped with means for readily removing the same from the mold when the same is ready to be poured. In 90 the present instance this consists of a lifting loop 11 which is substantially U-shaped and has its free end portions embedded in the main part of the sprue, the portion to be engaged by a suitable lifting tool being 95 within the cavity 4 as shown in Fig. 1. In other words the complete loop 11 is located inwardly of the plane of the flat surface 5 so that it will not interfere with the seating of the sprue.

I claim:

As a new article of manufacture, a sprue having a cavity in one end, and a lifting loop disposed in said cavity, said loop being positioned inwardly of the plane of the end 105 of the sprue.

In testimony that I claim the foregoing I have hereunto set my hand at Milwaukee, in the county of Milwaukee and State of Wisconsin.

CARL H. SCHMIDT
